UNITED STATES PATENT OFFICE.

FRITZ ACH, OF MANNHEIM, GERMANY, ASSIGNOR TO C. F. BOEHRINGER & SOEHNE, OF WALDHOF, GERMANY.

ALKYLIZED XANTHIN AND PROCESS OF MAKING SAME.

SPECIFICATION forming part of Letters Patent No. 681,760, dated August 22, 1899.

Application filed March 4, 1898. Serial No. 672,543. (Specimens.)

To all whom it may concern:

Be it known that I, FRITZ ACH, a citizen of the German Empire, residing at Mannheim, in the Empire of Germany, have invented certain new and useful Improvements in the Art of Preparing Xanthins; and I do hereby declare the following to be a full, clear, and exact description of the invention, such as will enable others skilled in the art to which it appertains to make and use the same.

This invention relates to the manufacture of xanthins, and more particularly the preparation of 3-alkyl-xanthins.

In carrying out my invention I proceed from 3-alkyl-uric acids—such, for example, as 3-methyl-uric acid—first converting the same into 3-methyl-chloro-xanthins by the action of phosphorus-oxy-chlorid, and thereupon converting the chloro-xanthin into a xanthin proper or 3-alkyl-2-6-dioxy-purin by the aid of reducing agents.

Before proceeding with the specification I will state that I have herein adopted the nomenclature and system of numbering the carbon and nitrogen atoms of the purin nucleus, which has been introduced by Prof. Emil Fischer and described in *Berichte der Deutschen Chemischen Gesellschaft*, Vol. 30, page 549. According to this system the purin nucleus is arranged and its atoms are numbered thus:

According to this nomenclature and system, xanthin, *e. g.*, whose formula is:

is denominated 2-6-dioxypurin and chloro-caffein, having the formula:

is 1-3-7-trimethyl-8-chloro-xanthin or 1-3-7-trimethyl-8-chloro-2-6-dioxy-purin.

In my application filed February 18, 1898, Serial No. 670,847, (Case J,) I have described and claimed generically the method of proceeding from alkyl-uric acids, having no alkyl in the position (9) first to alkylized chloroxanthins by the agency of phosphorus-oxy-chlorid and then from such alkylized chloroxanthins to higher alkylized products by alkylization and reduction, or vice versa. In that application I have also described and claimed the more specific method of applying the above treatment to 3-alkyl-uric acids and more particularly 3-methyl-uric acid. Among other things I claim in that application the method of preparing 3-alkyl-chloro-xanthin and specially 3-methyl-chloro-xanthin from 3-methyl-uric acid and also the said new compound 3-methyl-chloro-xanthin. 65 70 75 80

The invention forming the subject-matter of the present application consists in the preparation of 3-alkyl-xanthin, and, specifically, 3-methyl-xanthin from 3-alkyl-chloro-xanthin, and, specifically, 3-methyl-chloro-xanthin in the new compound thus produced, and also in the methods of proceeding therefrom to higher alkylized xanthins, such as theobromin and caffein. 85

In order to fully disclose my invention, I will first describe the method of preparing the starting material, 3-methylchloro-xanthin from 3-methyl-uric acid, it being understood that this method and the resulting compound are not herein claimed, since they form the subject-matter of the claims of my aforesaid application. 90 95

1. Preparation of 3-methyl-chloro-xanthin from 3-methyl-uric acid.—One part of anhydrous 3-methyl-uric acid is added to five parts, by volume, of phosphorus-oxy-chlorid and heated under pressure—*e. g.*, in a digester—to from 130° to 140° centigrade, and maintained at this temperature for from three to four hours, the mass being steadily agitated. The resulting clear reddish-brown solution is 105

then evaporated *in vacuo* for the purpose of completely removing the phosphorus-oxy-chlorid. The brownish residue, which has a tough varnish-like consistency, is thereupon brought into solution by boiling the same with about five times its quantity of alcohol or water. The alcoholic solution, which at first is clear, but soon becomes turbid on account of the precipitation of granular crystalline methyl-chloro-xanthin, is boiled for from two to three hours with reflux and then allowed to cool. Upon then filtering the methyl-chloro-xanthin remains on the filter as a yellow, granular, crystalline mass. The filtrate is then evaporated, whereby a second crystallization ensues, resulting in a further yield of the above product, methyl-chloro-xanthin. The crude product so obtained is brought into solution with dilute alkali, such as two-per-cent. potash-lye, treated with animal charcoal or other decolorizing agent, and finally precipitated with dilute sulfuric acid. On cooling the new compound is obtained in the form of yellow-hued coarse crystals, from whose analysis are obtained figures which show the formula of this compound to be $C_6H_5N_4O_2Cl + H_2O$. Its structural formula is found to be:

such formula being established by the fact of the ready conversion of this compound into chloro-caffein (see under II^a.) I therefore designate this new compound as "3-methyl-chloro-xanthin" or "3-methyl-8-chloro-xanthin."

The tenaciously-adhering yellow tint, which is very difficult of removal, has no influence on the percentage composition of the product.

Absolute decoloration of the methyl-chloro-xanthin may be attained by thoroughly boiling it with a large quantity (thirty parts to one part of the methyl-chloro-xanthin) of aceton. The xanthin is thereby gradually brought into solution, while the adhering coloring-matter remains undissolved. Upon cooling after such solution is effected the methyl-chloro-xanthin crystallizes in anhydrous, fine, colorless, shining foliated crystals or scales.

3-methyl-chloro-xanthin is soluble in about two hundred and fifty parts boiling water, and on cooling the solution slowly the same crystallizes therefrom in coarse needles, which under the microscope are found to be elongated flat prisms and which contain one molecule of water of crystallization. This water of crystallization escapes on protracted heating at 120° centigrade. It is difficult of solution in boiling alcohol, in aceton, acetic-ether, benzene, or chloroform, readily solu-

ble in dilute alkalis, in ammonia, and soda or potash solutions. It is equally soluble in concentrated sulfuric acid and fuming hydrochloric acid. From a solution in the latter the original product is precipitated by water on standing for some time. Heated with chlorin water or with dilute nitric acid it gives a strong murexid reaction. An ammoniacal solution of the same added to an ammoniacal silver solution yields a gelatinous silver salt, which remains unchanged on boiling.

3-methyl-chloro-xanthin has no melting-point, but on being rapidly heated it begins to turn yellow at 320° centigrade and at about 345° centigrade it decomposes with effervescence. The 3-methyl-chloro-xanthin is then converted into the chlorin-free-xanthin by reducing methods—e. g., as follows:

2. Preparation of 3-methyl-2-6-dioxypurin or 3-methyl-xanthin from 3-methyl chloro-xanthin.—If one part, by weight, of 3-methyl-chloro-xanthin, described under head 1, is heated with ten times its weight of fuming hydriodic acid, a gradual solution and reduction of the chloro compound takes place, which is attended by a liberation of iodin. The heating (at a temperature of 90° to 100° centigrade) is continued and phosphonium iodid added from time to time until a clear colorless solution is formed. The solution is then evaporated, whereby the iodohydrate of this new base is thrown out in the form of coarse colorless prismatic crystals. After the evaporation has been continued to complete dryness the residue is taken up with water, which causes the iodohydrate to be decomposed and the methyl-xanthin to be isolated in the form of fine colorless needles. The practical yield corresponds to the theoretical. The base is recrystallized from boiling water and so obtained in the form of fine shining needles. Its formula is $C_6H_6N_4O_2$ or, structurally:

The reaction, as a result of which it is obtained, is expressed in the equation:

This new base, as a xanthin, gives a strong murexid reaction only with chlorin water, while if it is evaporated together with moderately-concentrated nitric acid it yields a 5 slightly-colored residue, which is dissolved in strong potash-lye, and thus forms a clear deep-yellow solution. It requires from three hundred to three hundred and thirty parts of boiling water for solution, but is readily 10 soluble in dilute alkalies and ammonia and also in concentrated sulfuric or hydrochloric acid. An ammoniacal solution of the same, when added to a solution of nitrate of silver, gives rise to a colorless silver salt consisting 15 of fine needles. This silver salt dissolves in a large excess of ammonia on heating and remains unchanged on boiling.

If a solution of the 3-methyl-xanthin in dilute nitric acid is added to nitrate of silver, a double salt, consisting of coarse acicular crystals intermeshed in the form of bunches, is thrown out. This double salt is readily soluble in hot water.

soluble in hot water.

3-methyl-xanthin has no melting-point.

25 When heated above 360° centigrade, it begins to become yellow, and on raising the temperature above 400° centigrade it is decomposed without melting. This new body differs from the compound heteroxanthin described in

30 Patents Nos. 617,985 and 617,986, dated January 17, 1899, only in the location of the methyl group. While in the latter compound this group is in the position 7, in the present compound it occupies the position 3. I have

35 found that this new compound—the 3-methyl-xanthin—may be readily converted into higher alkylized xanthins by alkylizing methods. Thus, *e. g.*, I may obtain either dimethyl- and trimethyl-xanthins, or, in other words,

40 theobromin and cafein by the same alkylizing agents, potash-lye combined with methyl-iodid under the influence of heat by simply varying the proportions of the ingredients.

45 *3. Preparation of 3-7-dimethyl-xanthin (theobromin) from 3-methyl-xanthin.*—Seven parts, by weight, of 3-methyl-xanthin are dissolved in twenty-six parts, by volume, of potash-lye (potassium-hydrate solution) of double normal strength, and fifty parts, by volume, of water, and after adding thereto eight parts, by weight, of methyl-iodid, heated to 80° centigrade, and maintained at this temperature for three hours while constantly agitating the same. After cooling the liquid will be found to be filled with a pulpy mass of colorless crystals. The mother-liquor is removed from these crystals by suction or otherwise, and they are then redissolved in and recrystallized from boiling water. The colorless crystals so obtained possess all of the characteristic properties of natural theobromin.

65 4. Preparation of 1-3-7-trimethyl-xanthin (caffein) from 3-methyl-xanthin.—One part, by weight, of 3-methyl-xanthin is dissolved in 6.8 parts, by volume, of double normal potash-lye, (potassium-hydrate solution,) and

fifteen parts, by volume, of water and heated to 80° centigrade, together with two parts, by weight, of methyl-iodid, this temperature being maintained for three hours and the mass constantly agitated. The clear liquid so obtained is highly evaporated and then extracted with chloroform. The fine acicular crystals resulting from this treatment have the melting-point 232° centigrade and all of the other properties of caffein. The reaction takes place according to the equation:

The yield in caffein obtained corresponds to the theoretical yield.

It will be seen, thus, that this new body—3-methyl-xanthin—is readily susceptible of conversion into higher alkylized products, such as the important compounds, theobromin and caffein.

What I claim, and desire to secure by Letters Patent of the United States, is—

1. The process which consists in submitting 3-alkyl-chloroxanthin to the action of a reducing agent, whereby a 3-alkylxanthin is produced. 105

2. The process which consists in submitting 3-methyl-chloroxanthin to the action of a reducing agent for the purpose of preparing 3-methyl-xanthin.

3. In the process of obtaining xanthins the step which consists in heating 3-methyl-chloroxanthin with hydroiodic acid and phosphonium-iodid.

4. The process which consists in adding hydroiodic acid and phosphonium-iodid to 3-methyl-chloro-xanthin and heating the mixture all in the proportions and under the conditions, substantially as specified, then evaporating the resultant solution to dryness and taking up the residue with water. 115 120

5. As a new chemical compound, 3-methyl-xanthin, having the formula above given, which is soluble in a large amount of boiling water, but readily soluble in dilute alkalies and ammonia, and also in concentrated sulfuric or hydrochloric acid, which crystallizes from boiling water in the form of fine shining needles; which has no melting-point, but becomes yellow on being heated above 360° , centigrade, and decomposes at a temperature above 400° , centigrade, which gives dissolved in dilute nitric acid with silver nitrate a double salt consisting of coarse acicular crys-

5   tals and which gives rise in ammoniacal solution, when added to a solution of silver nitrate, to a colorless silver salt, remaining unchanged on boiling.

6. The process which consists in treating 3-alkyl-xanthin with an alkylizing agent.

7. The process which consists in treating 3-methyl-xanthin with an alkylizing agent.

8. The process which consists in heating 3-methyl-xanthin with hydrate-of-potassium solution together with methyl-iodid, substantially as described.

9. The process which consists in treating 3-methyl-uric acid with phosphorus-oxy-chlorid in the manner substantially as set forth

and then reducing the resulting 3-methyl-chloro-xanthin.

10. The process which consists in treating 3-methyl-uric acid with phosphorus-oxy-chlorid in the manner substantially as set forth, 20 then reducing the resultant 3-methyl-chloro-xanthin, and finally alkylizing the resultant 3-methyl-xanthin.

In testimony whereof I affix my signature in presence of two witnesses.

FRITZ ACH.
